COVER FOR FIRE ALARM OR SIMILAR ARTICLE

David K. Walz, Stone Mountain, Ga., assignor to Orkin
Exterminating Company, Inc., Atlanta, Ga., a corporation of Delaware

Filed Mar. 8, 1968, Ser. No. 10,898

Term of patent 14 years

(Cl. D72—1)

FIG. 1

FIG. 4

FIG. 1 is a front view of a cover for a fire alarm or similar article showing my new design;

FIG. 2 is a right side elevation thereof; and

FIGS. 3 and 4 are sectional views taken along the lines 3—3 and 4—4 in FIG. 1.

I claim:

The ornamental design for a cover for fire alarm or similar article, substantially as shown.
